UNITED STATES PATENT OFFICE

1,988,445

ROTATION DEVICE FOR DRILLING
MECHANISMS

Dudley K. Dovell, El Paso, Tex., assignor to Sullivan Machinery Company, a corporation of Massachusetts

Application July 29, 1930, Serial No. 471,581

3 Claims. (Cl. 121—7)

This invention relates to drilling mechanisms and more particularly to improved means for controlling drill steel rotation of a fluid pressure actuated hammer type drill.

5 In various types of drilling mechanism, especially of the pneumatic hammer type, the drill steel is intermittently rotated by the hammer piston through a pawl and ratchet mechanism cooperating with a rifle bar and nut. In certain 10 types of drilling mechanisms, such as stoppers, it is particularly desirable to be able to disconnect the drill steel rotating mechanism while permitting continued reciprocation of the hammer piston.

15 It is an object of my invention to provide improved means whereby the drill steel rotating mechanism may be variably controlled while permitting continued reciprocation of the hammer piston. A further and more specific object 20 is to provide improved means for releasing the ratchet of the pawl and ratchet rotating mechanism and in the specific aspect of the invention to provide an arrangement whereby the ratchet may be released by rotating a suitable member to 25 permit a pawl or other suitable stop element to be moved out of the path of the ratchet when it is desired to stop steel rotation.

Other objects and advantages will be more apparent to those skilled in the art and modifications 30 of my invention will likewise be readily apparent to such persons, from the following description of the accompanying drawing, in which,—

Fig. 1 is a side elevation of a stoper type of 35 drilling mechanism equipped with an illustrative form of the improved rotation control means;

Fig. 2 is an enlarged transverse section taken substantially on the line 2—2 of Fig. 1;

Fig. 3 is a fragmentary longitudinal section 40 through the drill motor showing the ratchet mechanism and hammer piston; and

Figs. 4 and 5 are elevational views of the cam for controlling the operation of the ratchet mechanism.

45 While I have shown my improved rotation control in connection with a drilling mechanism of the stoper type generally indicated at 1, it will of course be understood that the same may be applied to various other types of drilling tools 50 whether suitable for rock drilling or otherwise, although for various reasons the improved ratchet control is particularly applicable to a stoper type of hammer drill provided with a suitable feed, generally indicated at 3, and which 55 may be of the fluid actuated type or of any other

type, whereby a drill steel 4 carried in a usual chuck housing 5 may be fed with the drilling motor. The motor is of the conventional piston hammer type having a hammer piston 6 provided with a fluted striking bar 7, the flutes of which engage a suitable nut of the chuck whereby rotation of the piston will effect rotation of the chuck and in turn rotation of drill steel 4 in any usual manner. To effect piston rotation an internal ratchet 8, journaled in the rear head of the motor, cooperates with a series of spring pressed pawls 9. These pawls are pivotally supported in a suitable head 10 which has a bar 11 from which a rifle bar 12 extends for cooperation with a spiral nut 13 secured in a bore of the piston 6. Assuming the ratchet 8 to be held stationary, rearward movement of the piston 6 causes it to be partially rotated due to rifle bar 12 being held stationary by engagement of the pawls with the fixed ratchet. This partial 10 rotation of the piston is transmitted to the drill steel from striking bar 7 but upon forward movement of the piston the rifle bar 12 is partially rotated in a counterclockwise direction, as viewed 15 in Fig. 2, during which time the pawls 9 slip over the internal ratchet teeth. As is usual, successive reciprocating movements of the piston effects 20 a constant step by step rotation of the drill steel. In the type of motor herein disclosed a hollow 25 distributing sleeve valve 14 is provided for effecting the necessary fluid distribution to actuate the piston 6 and through which bar 11 extends.

To release the ratchet 8, thereby permitting the rifle bar 12 to oscillate during reciprocation of the piston 6 and hence not transmit any rotation thereto, the ratchet is provided with a peripheral groove 15 one end shoulder of which is adapted to be engaged by a radially movable stop pawl 16 suitably pivotally supported in a relatively wide recess 18 of the drill head, whereby when the stop pawl is moved to the other side of its wide recess, as shown in dotted lines in Fig. 2, the ratchet 8 may freely rotate as the rotation pawls are successively oscillated.

The means for holding the control or stop pawl 16 in operative position for effecting steel rotation comprises a pin 20 pressed into engagement with pawl 16, as by a cam 21 having a flat portion 22 which rides upon the inner end of pin 20. The cam 21 is actuated by any suitable 45 means such as a handle 23 and in addition is provided with a recess 24 for engagement with the reduced end of a lock pin 25. This lock pin 50 is held in position by a leaf spring 26 suitably secured at one end on the drill casing while the 55

other end freely engages the upper surface of the enlarged portion of pin 25, thereby pressing the lock pin into recess 24 and thus positively holding cam 21 in position to insure that pawl 16 is 5 positively held. The upper end of the lock pin is provided with a finger grip 27 whereby the pin may be raised to release cam 21. Upon this release, pawl 16 can move to its inoperative position, thereby permitting rotation of ratchet 8 in 10 a clockwise direction, as previously described, whereby no rotation will be transmitted to the steel although the piston may continue to reciprocate.

To prevent possible reverse rotation of the 15 ratchet ring during steel rotation, a pivoted spring-held stop pawl 30 engages a notch 31 in the ratchet periphery. This pawl is inclined so as to resist reverse rotation but permit forward rotation when the other stop pawl 16 is released, 20 and yet will drop into notch 31 when pawl 16 is moved from its inoperative to operative position. Groove 15 is of sufficient length to permit proper clearance for the swinging of pawl 16.

From the foregoing description it will be readily 25 apparent that drill steel rotation may be discontinued during continued reciprocation of the hammer piston merely by lifting lock pin 25 and rotating handle 23 in a clockwise direction whereupon the cut away portion 33 of cam 21 permits 30 holding pin 20 to move away from pawl 16 to permit it to move to its inoperative position. To reestablish steel rotation the handle 23 is rotated downwardly to the position shown in Fig. 2 thereby moving pin 20 and pawl 16 into the position 35 as shown, although it will of course be seen that if the peripheral groove 15 does not happen to be in such an angular position as to permit pawl 16 to drop therein, due to the ratchet 8 having been rotated, the pawl 16 will simply ride upon the 40 periphery of the ratchet until groove 15 is finally rotated around to the necessary position where pawl 16 will drop in. During such a condition the operator would merely maintain a light pressure upon the handle 23 until the groove is 45 engaged, whereupon the lock pin 25 would automatically fall into recess 24 and positively hold the device in operative condition. At the same time reverse pawl 30 will drop into notch 31.

While there is in this application specifically 50 described one form which this invention may assume in practice, it will be understood that this form of the same is shown for purposes of illustration and that the invention may be modified and embodied in various other forms without departing from its spirit or the scope of the appended claims.

What I claim as new and desire to secure by 5 Letters Patent is:

1. In a hammer drilling mechanism, tool rotation mechanism including pawl and ratchet elements, means whereby each of said elements is supported for rotation, means for holding one of said elements against rotation during normal tool rotation including a pair of relatively oppositely facing shoulders formed in fixed relation to the element to be held, a pair of relatively movable holding members, one arranged to engage one of said shoulders and the other to engage the other of said shoulders and each rotatable on an axis spaced from the axis of rotation of said pawl and ratchet elements into its shoulder engaging position, and means for causing said members concurrently to have engagement with the shoulders with which they respectively cooperate.

2. In a hammer drilling mechanism, tool rotation mechanism including a ratchet, means for rotatably supporting said ratchet, means for preventing rotation of said ratchet including relatively opposed shoulders adjacent the periphery of said ratchet, pivoted pawls rotatable on axes spaced from the axis of ratchet rotation and swingable on such axes, one into engagement 20 with one of said shoulders and the other with the other of said shoulders, and also swingable out of engagement with said shoulders, and means for at will holding one of said elements against swinging out of engagement with its cooperating 35 shoulder.

3. In a hammer drilling mechanism, tool rotation mechanism including a ratchet, means for rotatably supporting said ratchet, means for preventing rotation of said ratchet including relatively opposed shoulders adjacent the periphery of said ratchet, pivoted pawls rotatable on axes spaced from the axis of ratchet rotation and swingable on such axes, one into engagement 40 with one of said shoulders and the other with the other of said shoulders, and also swingable out of engagement with said shoulders, and a cam for positively swinging one of said pawls into engagement with its cooperating shoulder and locking it there.

DUDLEY K. DOVELL.
